UNITED STATES PATENT OFFICE.

JOSEPH A. SHOEMAKER, OF BROOKLYN, NEW YORK.

GARMENT HANGER.

Application filed April 22, 1921. Serial No. 463,452.

To all whom it may concern:

Be it known that I, JOSEPH A. SHOEMAKER, a citizen of the United States, residing at Brooklyn, in the county of Kings and State 5 of New York, have invented certain new and useful Improvements in Garment Hangers, of which the following is a specification.

This invention has relation to garment 10 hangers, and has for an object to provide a hanger having means upon which to support the coat portion of a suit or dress, and a cross bar upon which to support the folded trousers or skirt, the parts being jointed 15 for relative movement to permit the hanger to be folded for convenience in packing.

Another object of the invention is to provide a hanger providing a coat supporting means and a horizontal base connecting 20 member attached to the movable parts of the coat supporting means adjacent their outer ends and constructed and arranged to permit of the entire hanger to be folded and packed in a minimum of space.

In addition to the foregoing, this invention comprehends improvements in the details of construction and arrangement of parts to be hereinafter described and particularly set forth in the appended claims.

In the accompanying drawings in which similar and corresponding parts are designated by the same characters of reference throughout the several views in which they appear:

Figure 1 is a view in front elevation of a garment hanger constructed in accordance with my invention showing the same in extended position.

Figure 2 is a view thereof in edge elevation.

Figure 3 is a view of the hanger in front elevation and in folded position.

Figure 4 is a detail view.

Figure 5 is a detail section taken on the line 5—5 of Figure 4.

Figure 6 is a detail view of a slightly modified form of connection.

Figure 7 is a detail section taken on the line 7—7 of Figure 6.

With reference to the drawings, 10 and 11 indicate the coat supporting members of the hanger consisting of straight bars having their adjacent ends cut away as at 12 for overlapping engagement and an element 13 penetrating said ends to pivotally connect the members, said element 13 being

preferably of wire and bent to form a hook 14 whereby the entire device may be suspended. One of the edges of each bar is rounded as at 15. A combined brace and 60 garment supporting member 16 is provided in the form of a wooden bar, preferably circular in cross section. Each end of the member 16 is connected to the outer ends of the bars 10 and 11 through the medium of 65 a rectangular link 17 formed of a strand of wire bent to shape with the terminals inserted in openings formed in the members 10 and 11, the bight portion extending through an opening in the bar 16. I prefer 70 to employ a clip 18, substantially U-shaped in cross section to embrace the inner side of each member 10 and 11 and permit the terminals of the link to penetrate the sides 75 of the clip as shown, a lug or projection 19 being formed on each side of the clip.

It is to be noted that the aggregate length of both bars 10 and 11 is greater than the length of the brace 16. Thus, when the hanger is extended as in Figure 1 with the 80 bars 10 and 11 in angular relation, the outer ends of said bars will almost meet the ends of the brace 16. In this position the links 17 will converge toward the pivoted point of the members 10 and 11. To fold the 85 device the members 10 and 11 are brought into alignment as in Figure 3 the links permitting the brace 16 to move into contact and parallelism thereto. When extending or folding the hanger, in either 90 case the links will ride over the projection 19, creating slight friction which will cause the parts of the hanger to fall into proper position with a snap, thus assuring their retention in position against any casual dislodgment. Attention is drawn to the fact 95

that in its folded position the parts are all in a straight line which enables the hanger to be conveniently packed in baggage. Also it is to be noted that when in extended position and supporting a garment, the hanger may be grasped through the garment or at any point without possibility of collapse by reason of the fact that during folding movement it is necessary that the outer ends 105 of the bars 10 and 11 move apart slightly and this movement is resisted by the garment itself. Also, since in extended position the links converge toward the pivotal point of connection of the bars 10 and 11 110 as shown in Figure 1, the hanger may be grasped by the brace 16 without collapse

since in closing it would be necessary for the cutter ends of the bars 10 and 11 to first move upward a slight distance which movement would be resisted by the weight 5 of the garment. The trousers or skirt may be folded and laid across the brace 16, and the weight of the garment will afford another means for retaining the hanger against collapse. It is to be observed that the outer 10 ends of the members 10 and 11 contact against the ends of the brace 16 when the device is in extended position. The brace 16 will thus take up the strain upon the links 17 and prevent wear around the openings through which the links extend.

A form of connection in lieu of the link is shown in Figure 6 consisting of a strip 20 secured at its ends to the edge of the members 10 and 11 with the intermediate 20 portion of the strip spaced from the member but curved inward slightly. Each end of the brace 16 carries a sleeve 21, split to form opposed ears 22, with the edges of the split portion serrated to penetrate the brace. A pin 23 connects the ears and is located between the strip 20 and the member 10 or 11 to which it is connected. In this manner relative movement between the brace and members 10 and 11 in a rectilinear direction is permitted, the curve of the strip causing the parts to fall into extended or folded position with a snap.

While I have illustrated and described my invention with some degree of particularity, 35 I realize that in practice various alterations may be made therein. I therefore reserve the right and privilege of changing the details of construction, or altering the arrangement of the parts, without departing from the spirit of the invention or the scope 40 of the appended claims.

Having thus described my invention, what I claim as new and desire to secure by United States Letters Patent is:

45 1. A garment hanger including a pair of

bars, means pivoting one of their ends together for relative movement, a brace bar 50 lesser in length than the aggregate length of both of said first mentioned bars, and a link at each end of the brace bar, said links being pivotally connected to the free ends of the first mentioned bars, the links being of a length to cause the ends of the brace and the free ends of the bars to mutually engage when the hanger is ex- 55 tended.

2. A garment hanger including a pair of pivoted bars, a clip at the free end of each bar, a brace, and a link at each end of the brace also penetrating the bars and the clips, 60 and a projection on each clip for frictionally engaging the links during movement of the parts from a folded to an extended position to resist movement of the parts at either extremity of their movement. 65

3. A garment hanger of the character described including two members pivoted together at an end of each, a brace bar of less length than the combined length of the two members, and a link connecting each 70 end of said bar with a corresponding free end of said pivoted members, so that the members may be folded in parallelism with the free bar in collapsed position of the hanger. 75

4. A garment hanger of the character described including two members pivoted together at an end of each, a brace bar of less length than the combined length of the two members, links connecting the ends of said bar with said members at a point inwardly of the corresponding free ends of said pivoted members, so that the ends of said members may slightly raise during the act of folding the same in parallelism with the free bar as the hanger is brought into collapsed position. 80

In testimony whereof I affix my signature.

JOSEPH A. SHOEMAKER. [L.S.]
